UNITED STATES PATENT OFFICE

ROBERT ADWIN THOMPSON, OF CLEVELAND, TENNESSEE, ASSIGNOR TO HARDWICK STOVE COMPANY, OF CLEVELAND, TENNESSEE, A FIRM COMPOSED OF CHRISTOPHER L. HARDWICK AND COOKSEY H. HARDWICK

DESIGN FOR A PANEL FOR A STOVE DOOR OR THE LIKE

Application filed December 22, 1931. Serial No. 42,180. Term of patent 7 years.

To all whom it may concern:

Be it known that I, ROBERT ADWIN THOMPSON, a citizen of the United States of America, residing at Cleveland, in the county of Bradley and State of Tennessee, have invented a new, original, and ornamental Design for a Panel for a Stove Door or the like, of which the following is a specification, reference being had to the accompanying drawings, forming a part hereof.

In the drawings, Fig. 1 is an elevation of a panel showing my new design.

Fig. 2 is an edge view of the same.

The panel is a complete article of manufacture.

I claim:

The ornamental design for a panel for a stove door or the like, as shown and described.

ROBERT ADWIN THOMPSON. [L. S.]
